[57] CLAIM

The ornamental design for an electronic bicycle bell, as shown and described.

DESCRIPTION

FIG. 1 is a right side elevational view of an electronic bicycle bell showing my new design, with the left side being a mirror image thereof;

FIG. 2 is a top plan view thereof;

FIG. 3 is a right side elevational view thereof shown in fastened condition when in use;

FIG. 4 is a top plan view thereof;

FIG. 5 is a bottom plan view thereof;

FIG. 6 is a front elevational view thereof;

FIG. 7 is a rear elevational view thereof; and

FIG. 8 is a perspective view thereof.

FIG. 1

FIG. 2

FIG. 3

FIG. 4

FIG. 5

FIG. 6

FIG. 7

FIG. 8
